ELECTRIC IRON

Austin E. Cox, Wadsworth, Ohio, assignor to Dominion Electric Corporation, a corporation of Ohio

Filed Oct. 18, 1965, Ser. No. 87,546

Term of patent 14 years

(Cl. D49—1)

FIGURE 1 is a plan view of an electric iron embodying my new design;

FIGURE 2 is a side view of the same, the opposite side being substantially the same in appearance;

FIGURE 3 is a bottom view of the same;

FIGURE 4 is a front view of the same; and

FIGURE 5 is a rear view of the same.

The electric cord is shown broken away in FIGURES 1, 2 and 5 for convenience of illustration.

The dominant features of my design reside in the portions shown in full lines, being characterized by the handle portion of the disclosed electric iron as shown.

I claim:

The ornamental design for an electric iron, substantially as shown and described.
